Roland A. Manning, Milwaukee, Wis., assignor to
The Electric Sprayit Co., a corporation of Del-
aware

Application September 2, 1938, Serial No. 79,721

Term of patent 7 years

To all whom it may concern:

Be it known that I, Roland A. Manning, a citizen of the United States, residing at Milwaukee, in the county of Milwaukee and State of Wisconsin, have invented a new, original, and ornamental Design for a Sprayer, of which the following is a specification, reference being had to the accompanying drawing, forming part thereof,

Fig. 1 is a side elevational view of a sprayer showing my new design;

Fig. 2 is a rear elevational; and

Fig. 3 is a top plan view thereof.

I claim:

The ornamental design for a sprayer, substantially as shown.

ROLAND A. MANNING.
